SYSTEM OF ELECTRIC-CIRCUIT CONTROL.

1,017,052.

Specification of Letters Patent. Patented Feb. 13, 1912.

Application filed March 9, 1908. Serial No. 420,062.

To all whom it may concern:

Be it known that I, FORD W. HARRIS, a citizen of the United States, and a resident of Wilkinsburg, in the county of Allegheny 5 and State of Pennsylvania, have invented a new and useful Improvement in Systems of Electric-Circuit Control, of which the following is a specification.

My invention relates to automatic circuit 10 interrupters and circuit control systems embodying such devices and it has for its object to provide a system of the aforesaid class that shall be simple in arrangement and adapted to effect the introduction of a 15 time element into the automatic operation of the interrupter without interfering with its remote control by an attendant.

Automatic circuit interrupters are frequently situated where they are not readily 20 accessible and, in such cases, it is desirable to completely govern their operation from a distant point. For example, in a high voltage line construction for electric railways, oil-immersed circuit interrupters are 25 employed for providing a shunt circuit about a section-break insulator, the circuit interrupters being located on the structure which supports the line conductor.

According to my present invention, I provide 30 a switching device or controller which may be situated in a signal tower or at any other convenient point and which is adapted to introduce an auxiliary circuit interrupter having a time element, in shunt to the tripping coil of the main circuit interrupter during 35 the automatic operation of the interrupter, the time element device being removed from the circuit whenever it is desirable to change the position of the main 40 interrupter at the will of an attendant.

The single figure of the accompanying drawing is a diagrammatic view of a system arranged in accordance with my invention.

Referring to the drawing, a main line conductor 1 is divided into sections by an insulating section break 2 which may be shunted by means of a circuit interrupter 3. The circuit interrupter comprises stationary contact members 4, a coöperating movable contact member 5, an operating lever 6, an actuating magnet 7 and a release magnet 8. The operating lever 6 is normally connected to a movable member 9 of the magnet 7

by means of a link 10, a bell crank lever 11, a latch 12, a lever 13 having a roller 14 that is engaged by a hooked projection 15 from the movable core member and a gib 16 which is engaged by the latch 12. When the circuit interrupter is closed the stationary 60 and movable contact members may be held in engagement with each other, independently of the operating magnet, by means of a second latch 17 which is rotatably mounted on a stationary shaft 18 and is adapted to engage the gib 16. The tripping magnet 8, when energized, acts through a bell crank lever 19 and a link 19^a, in opposition to a spring 20, to withdraw the latch 12 from the gib 16 and thus permits the movable 70 contact member to fall.

The latch 17 is in the form of a bell crank lever and is provided with an arm 21 which is engaged by a projection 22 on the lever 6, when the stationary and movable contact 75 members are separated from each other, to effect such rotative movement in opposition to a spring 23 as to disengage the latch 17 from the gib 16. The movable core member 9 of the magnet 7 is thus permitted to drop 80 unless the magnet winding is energized.

The operation of the circuit interrupter is automatically dependent upon the current traversing the main circuit since the tripping coil 8 is directly connected to the secondary winding 24 of a series transformer 25, but its action may also be made responsive to the will of an attendant at any distant point by means of a controller 26 which is adapted to occupy any one of positions *a*, *a*, and *y*. The position of the main circuit interrupter is indicated by lamps 27 and 28 which may be replaced by any other suitable visible or audible indicators and which are preferably located near the controller 26. 95

An auxiliary switch 29, which comprises stationary contact members 30 and 31 and a movable contact arm 32 is operatively connected to the lever 6 by means of a link 33, the movable contact arm being moved into 100 engagement with the one or the other of the stationary contact members according as the main circuit interrupter is opening or closing.

A fuse 34, or other suitable circuit interrupter having a time element, is connected in shunt circuit relation to the tripping coil 8 under certain conditions, hereinafter pointed

2

out, for the purpose of preventing the automatic interruption of the main circuit when harmless fluctuations occur in the main circuit current.

5 The operation of, and the circuit connections for, the device are as follows: Assuming that the controller 26 occupies its position *a*, as shown in the drawings, and that the circuit interrupter 3 is closed, it 10 will be observed that the tripping coil 8 is energized in accordance with the current traversing the main circuit, circuit connections being established from one terminal 35 of the series transformer 25 through a conductor 36, tripping coil 8 and conductor 37 to the opposite transformer terminal 38. A shunt circuit to the tripping coil is established from the conductor 36 through conductors 39 and 40, fuse 34, conductor 41, 15 contact fingers 42 (that are bridged by contact member 43 when the controller 26 occupies the position *a*), conductor 44, movable contact member 32, stationary contact terminal 31 and a conductor 45 to the conductor 37 which is joined to the opposite terminal of the tripping coil. The resistance of the fuse 34 relative to that of the tripping coil is such that the current traversing the tripping coil is not sufficient to release the 20 latch 12 and the circuit traversing the fuse under normal conditions in the main circuit is not sufficient to rupture the shunt circuit established through it. It will be readily understood that if the main circuit current 25 rises above the predetermined normal value for a relatively short time the fuse will not be ruptured but if the abnormal current continues for a considerable length of time the fuse will be over-heated and the shunt circuit will be interrupted. Immediately following such interruption, the current traversing the tripping coil will be considerably increased and the latch 12 will be released from the gib 16 in opposition to the spring 20, thereby permitting the circuit breaker to open and the movable member 9 of the operating magnet 7 to drop, as above indicated. The fuse 34 is preferably located 25 near the controller 26 so that it may be readily replaced when it is destroyed. The circuit interrupter may be closed by so moving the drum of the controller 26 that it shall engage the fingers along the line *y* to establish an auxiliary circuit from one terminal 35 46 of any suitable source, such as a generator 47, through conductor 48, contact fingers 49 and 50 (which are bridged by a contact member 51 when the controller 26 occupies this position), conductor 52, winding 53 of the operating magnet 7, and conductors 39 and 40 to the opposite terminal 54 of the generator 47. When the fuse 34 is replaced and the main circuit interrupter is closed 60 the drum of the controller 26 may be re-turned to engage the fingers along line *a* in

which automatic operation of the interrupter is permitted. If it is desired to open the circuit interrupter at the will of an attendant without rupturing the fuse 34, the controller drum may be moved to engage the 70 fingers along line *x* in which fingers 49 and 48 respectively engage connected segments 55 and 56 to establish a circuit from the terminal 46 of the generator 47 through conductor 48, contact finger 49, contact segments 75 55 and 56, contact finger 42, conductor 44, switch arm 32, contact terminal 31, conductor 45, tripping coil 8 and conductors 39 and 40 to the terminal 54 of the generator 47. When the main circuit interrupter is closed and the 80 auxiliary switch arm 32 engages contact member 31, the indicator 28 is energized, circuit being established from conductor 48 through the switch 29, conductor 45, tripping magnet 8 and conductor 39 to the auxiliary conductor 40, and when the circuit interrupter is opened the indicator 27 is actuated, circuit being established from conductor 48 through contact member 30, switch arm 32, conductor 44 and the indicating device 27 to auxiliary line conductor 40. 85 90

Although I have illustrated a type of circuit interrupter specially adapted for use in my improved circuit control system, and although I have shown a fuse as a time element feature, my invention is not restricted in this regard and it is conceivable that modifications in the arrangement of the circuits of the system as well as modifications in the structure of the interrupter or type 100 of time element device may be effected within the scope of my invention. Consequently I desire that only such limitations shall be imposed as are indicated in the appended 105 claims.

I claim as my invention:

1. The combination with a main circuit and an interrupter therefor having stationary and movable contact members, means for holding the members in engagement with each other, electro-magnets for operating the movable contact member and for releasing the holding means, and a circuit interrupter having a time element, of an auxiliary circuit and a controller for selectively 110 supplying energy to the electro-magnets and for connecting the interrupter having a time element in shunt circuit relation to the release magnet. 115

2. The combination with an automatic circuit breaker having stationary and movable contact members and operating and release magnets, an auxiliary switch controlled by the movable member and a circuit interrupter having a time element, of a remote controller to act in conjunction with the auxiliary switch and connect the circuit interrupter having a time element in shunt circuit relation to the release magnet. 125

3. In a system of electric circuit control, 130

- the combination with a main circuit, an interrupter therefor having stationary and movable contact members, an operating magnet and a release magnet having independent 5 windings, an auxiliary circuit and connections from the release magnet to the main circuit and to the auxiliary circuit, of remote means for introducing a time element into the automatic operation of the breaker.
- 10 4. In a system of electric circuit control, the combination with a main circuit, an interrupter having stationary and movable contact members, an operating magnet and an automatic release magnet having independent 15 windings, an auxiliary circuit and connections from the release magnet to the main circuit and to the auxiliary circuit, of remote means for governing the operation of the circuit interrupter and for introducing 20 a time element into its automatic operation.
5. In a system of electric circuit control, the combination with a main circuit, an interrupter having stationary and movable 25 contact members, an operating magnet and an automatic release magnet having independent windings, an auxiliary circuit and connections from the release magnet to the main circuit and to the auxiliary circuit, of 30 a controller for selectively supplying energy from the auxiliary circuit to the electro-magnets and for connecting an auxiliary circuit interrupter having a time element in shunt circuit relation to the release magnet.
- 35 6. The combination with an automatic circuit breaker having operating and release magnets, of a remote controller for governing the automatic operation of the circuit breaker and for connecting a fuse in shunt 40 relation to the release magnet.
7. The combination with a main circuit and an interrupter having stationary and movable contact members, means for holding the members in engagement with each 45 other, electro-magnets for operating the movable member and for releasing the holding means, of a fuse and an auxiliary circuit controller for selectively supplying energy to the electro-magnets and for connecting the 50 fuse in shunt circuit relation to the release magnet.
8. The combination with an automatic circuit breaker having stationary and movable contact members and operating and release 55 magnets, an auxiliary switch controlled by the movable member, and a fuse, of a remote controller acting in conjunction with the auxiliary switch to connect the fuse in shunt circuit relation to the release magnet.
9. In a system of electric circuit control, the combination with a main circuit, an interrupter therefor having stationary and movable contact members, an operating magnet and a release magnet having independent windings, an auxiliary circuit and connections from the release magnet to the main circuit and to the auxiliary circuit, and a fuse, of a controller for governing the operation of the circuit interrupter and for introducing a time element into its automatic 65 operation by associating the fuse with the release magnet.
10. In a system of electric circuit control, the combination with a main circuit, an interrupter therefor having stationary and movable contact members, an operating magnet and a release magnet having independent windings, an auxiliary circuit and connections from the release magnet to the main circuit, and to the auxiliary circuit, of a controller for selectively supplying energy from the auxiliary circuit to the electro-magnets and for connecting a fuse in shunt circuit 70 relation to the release magnet.
11. The combination with a circuit interrupter having electro-responsive operating means, a release magnet and a winding therefor, of a time element circuit interrupter in shunt circuit to the release magnet and remote means for concurrently excluding the 75 time element circuit interrupter and actuating the operating means.
12. The combination with a circuit breaker having a release magnet winding and a fuse in shunt circuit therewith, of remote means 80 for excluding the fuse and operating the breaker.
13. The combination with a circuit breaker having an automatic release magnet winding and a fuse acting in conjunction therewith, of manually-operated remote means for excluding the fuse and operating the circuit breaker.
- In testimony whereof, I have hereunto subscribed my name this 21st day of February, 1908.
